(57) **CLAIM**

The ornamental design for an exhaust system clamp, as shown and described.

DESCRIPTION

FIG. 1 is a front perspective view of a first embodiment of an exhaust system clamp, according to the present invention; FIG. 2 is a front view of the exhaust system clamp of FIG. 1; the rear view being substantially identical thereto;

FIG. 3 is a right side view of the exhaust system clamp of FIG. 1;

FIG. 4 is a left side view of the exhaust system clamp of FIG. 1;

FIG. 5 is a top view of the exhaust system clamp of FIG. 1; FIG. 6 is a bottom view of the exhaust system clamp of FIG. 1;

FIG. 7 is a front perspective view of another embodiment of an exhaust system clamp, according to the present invention; FIG. 8 is a front view of the exhaust system clamp of FIG. 7;

FIG. 9 is a right side view of the exhaust system clamp of FIG. 7;

FIG. 10 is a rear view of the exhaust system clamp of FIG. 7;

FIG. 11 is a left side view of the exhaust system clamp of FIG. 7;

FIG. 12 is a top view of the exhaust system clamp of FIG. 7;

FIG. 13 is a bottom view of the exhaust system clamp of FIG. 7;

FIG. 14 is a top view of the clamp of FIG. 1 with the bolt partially broken away; and,

FIG. 15 is a top view of the clamp of FIG. 7 with the bolt partially broken away.
